APPARATUS FOR SPRAYING THE INTERIOR OF CYLINDRICAL ARTICLES

Donald R. Goetchius, Avon, Ohio, assignor to
Ferro Enamel Corporation, Cleveland, Ohio, a
corporation of Ohio

Application May 17, 1946, Serial No. 670,438

7 Claims. (Cl. 91—44)

1

This invention relates as indicated to an apparatus for spraying the interior surface of a hollow article of manufacture such as for example the cylindrical casing of a domestic hot water tank.

It is one principal object of this invention to provide an apparatus capable of uniformly spraying the interior of such articles.

It is another object of this invention to provide an improved apparatus for breaking up a liquid spray material into a fine mist or fog and thrusting the same in a generally radially outward direction by centrifugal force against the interior wall of the article being sprayed.

Another object of this invention is to provide a control mechanism for coordinating the movement of a conveyor which carries the article to be sprayed with the reciprocating movements of a spray head so that they will move successively and never simultaneously.

Another object is to provide an improved control mechanism which makes possible continuous uninterrupted operation of the apparatus as a whole; that is the spraying apparatus and the article carrying conveyor.

Another object of this invention is to provide a spraying apparatus in which the acceleration and deceleration of the spray head at the limits of its reciprocating movements are not effective to deposit a heavier coating at the ends of the article being sprayed than in an intermediate portion thereof.

Another object of this invention is to provide novel means for raising and lowering the spray head at uniform rates of speed.

Additional objects and advantages of the invention will become apparent as the following description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In the drawings:

Fig. 1 is a front elevation view of the apparatus as a whole;

2

Fig. 2 is a top plan view of the apparatus clearly showing the motor and means for reciprocating the spray head;

5 Fig. 3 is an enlarged view of the lower end of the spray head;

Fig. 4 is an enlarged view looking down into the spray cup from the upper open end thereof; and

10 Fig. 5 is a wiring diagram for accomplishing the desired automatic control of the apparatus.

Referring now to the drawing and first to the mechanical structure shown in Figs. 1-4 there is shown therein a frame structure comprising a base plate 1 to which is secured two parallel and vertical H columns 2. The upper ends of the H columns are tied together by a cross beam 3 secured to each column. Suitable side channels 4 and rear channels 5 welded to the base plate and to the upper ends of the columns and suitable tie members 6 welded to the columns and to the side and rear channels serve to provide a rigid integral frame structure.

15 Between the columns 2 and extending upwardly from the base plate 1 is a spray booth which comprises side panels 7 spaced from opposed faces of the columns 2 and a top panel 8 provided with a vent nipple 9 to which a pipe can be connected for drawing away any fumes which might result from the spraying. The booth is secured to the frame by means of brackets 10. It is to be noted that the brackets 10 are disposed toward the lower end of the frame and that the spray booth is spaced from the opposed faces of the columns 2 in order that the spray booth will not in any way interfere with the free movement of the hereinafter to be described spray head.

20 The spray head as a whole comprises a pair of vertical jibs 11 rigidly secured to a horizontally disposed cross arm 12, the latter having secured thereto a hollow downwardly extending sleeve 13. The lower end of sleeve 13 carries the spraying device which constitutes one of the essential features of this invention and which will be presently described with greater particularity. The spray head is guided in its upward and downward reciprocating movements by means of a groove in the outer face of each jib 11 which straddles the flange of the adjacent column 2.

25 The mechanism for reciprocating the spray head comprises a reversible variable speed elec-

tric motor 14 which is supported on a shelf 15 on the frame and which, through a sprocket wheel and chain 16, drives a reel 17 in one direction or the other to wind or unwind a cable 18 thereto or therefrom. The cable has one end thereof secured to the cross beam 3 and passes over a pulley 19 rotatably mounted on cross arm 12 and over other suitable pulleys 20 on the cross beam 3 and the other end thereof is secured to the reel 17. Thus, it can be seen that rotation of reel 17 in a clockwise direction as viewed in Fig. 1 will hoist the spray head upward, whereas rotation thereof in a counterclockwise direction will permit the spray head to drop downward by gravity but at a rate determined by the speed of rotation of reel 17. The essential elements for controlling the motor 14 are mounted on a suitable panel 21 on the right-hand front side of the frame.

The spraying device comprises a spray cup 22 at the lower end of sleeve 13, said cup being rotated by means of an air motor 23 of any conventional type adapted to translate force exerted by air flowing under pressure supplied through conduit 24 into rotation of the drive shaft 25 to which the cup is securely fastened. Conduit 24 is preferably disposed within the sleeve 13 and at the upper end such conduit is flexible and communicates with a suitable source of air under pressure. The flexible portion of the conduit permits free upward and downward movement of the spray head. Spray cup 22 is generally spherical at its bottom portion and the side wall thereof is flared outwardly and upwardly as viewed in Fig. 3. The upper portion thereof is provided with a plurality of slits 26 which are preferably V-shaped. One simple manner of making such V-slots is to first use an ordinary saw blade to make the slits and then flare the upper portion, thereby causing the slits to spread apart at the upper ends thereof. The spray cup is intended to be continuously rotated. Therefore, no control means are necessary other than the usual shut-off means for discontinuing rotation when the apparatus is not in use.

Within cup 22 and converging toward the bottom thereof are two discharge nozzles 27 through which liquid spray material is forced toward the bottom of the cup. It can be seen that rotation of cup 22 effects radial outward and upward movement of the spray material through the slits to break up such material into a fine mist or fog and to throw the same by centrifugal force against the interior of the article being sprayed.

Spray material is furnished to the discharge nozzles 27 through a conduit 28 preferably fastened on the outside of sleeve 13 and along the cross arm 12. The outer end of conduit 28 is flexible and is connected to a source of spray material under pressure. Interposed in conduit 28 is a normally closed valve 29 which can be opened to permit flow of spray material to the nozzles by depressing the projecting stem portion thereof. As shown in Fig. 1, valve 29 is fastened on a bracket 30, which bracket in turn is secured on one of the jibs 11. Adjustably fastened on one flange on one of the columns 2 is a cam bar 31 which is engageable with the aforesaid valve stem to open the valve and keep it open during reciprocation of the spray head and disengageable with said stem when the spray head reaches its upper limit, thereby permitting closing of the valve and consequent stopping of the spraying.

Briefly, the reciprocating cycle of the spray

head is commenced by manually operating a push button 32 which in turn energizes a magnetic switch 33 to establish a circuit to motor 14 to effect rotation thereof in a counter-clockwise direction as viewed in Fig. 1. This permits controlled downward gravity movement of the spray head until tripper arm 34 on jib 11 trips switch 35, whereupon the magnetic switch 33 is energized to reverse the direction of rotation of motor 14. This reversed rotation lifts the spray head upward at the predetermined rate of speed and such upward movement continues until tripper arms 34 trips switch 36, whereupon the magnetic switch 33 is deenergized to open the motor circuit and thereby stop the motor. Switches 35 and 36 are mounted on separate plates 37 which plates are adjustably mounted along one of the columns 2 and are locked in adjusted position by means of screws 38. During the aforesaid reciprocation of the spray head valve 29 was in open position permitting spray material to be supplied to the spray cup 22.

As will be presently explained, the tripping of switch 36 in addition to opening the motor circuit is operative to commence movement of a conveyor 39 and then tripping of a switch 40 by the conveyor is operative to stop the conveyor and to initiate downward movement of the spray head. Switches 35, 36 and 40 are preferably of the type which are normally in the positions shown in Figs. 1 and 5 and which, when tripped, will only momentarily make or bridge the other pair of contacts therein. Switch 41 is a main line switch and switches 42 and 43 are safety switches to cut off the power line in the event that switches 35 or 36 should become inoperative to respectively reverse or stop the motor 14.

As shown in Fig. 1, the spray booth is open in the front and rear and a conveyor 39 passes therethrough. Said conveyor is of the usual construction and preferably includes an endless belt 44 which is driven by means of an electric motor 45 controlled in part by means of a push button switch 46 and a magnetic switch 47. Motor 45 and switches 46 and 47 are not shown in Figs. 1-4 but are shown schematically in Fig. 5. The conveyor belt 44 is provided with several sets of locating blocks 48 thereon for positioning the tank T thereon with its open bottom edge spaced from the belt 44 for reasons which will become apparent as the description proceeds. Mounted on one of the columns 2 is a switch 40 which is adapted to be tripped by means of an arm 49 on belt 44. Arm 49 is disposed relative to blocks 48 so that when switch 40 is tripped to shut off the conveyor motor, the tank T will be directly below the spray cup 22 and coaxial therewith. In this way if the tank T is cylindrical every portion of it will be equidistant from the spray cup to assure uniform spraying thereof.

Having adjusted the arm 49 relative to switch 40, the switches 35 and 36 should be adjusted so that the upper limit of the spray cup 22 is somewhat above the top edge of the tank T to be sprayed and the lower limit thereof is somewhat below the bottom edge of the tank T to be sprayed. Likewise, cam bar 31 should be adjusted to a position such that valve 29 will be opened prior to the spray cup moving down to a position in line with the top edge of the tank. By adjusting the switches and cam bar as aforesaid, uniform spraying is assured because spraying of the tank is effected only while the spray

cup is reciprocating at a uniform rate of speed. That is to say that the tank is in spraying position radially opposite the spray cup only during the uniform reciprocation thereof and not during the acceleration and deceleration thereof as occurs at the upper and lower limits of its movement.

Having thus described the specific structure of the apparatus and its general operation, reference will now be made to the wiring diagram of Fig. 5 in describing the operation of the apparatus in detail.

With the switches in the normal positions shown and with the spray head at its upper position and a tank T in spraying position, the main line switches 41 and 50 can be closed. In the present embodiment of the invention I prefer to use current from a three-phase 220 or 440 volt line, although it is contemplated that an ordinary 110 volt A. C. or D. C. line could be satisfactorily used. In order to initiate downward movement of the spray head, button 32 of the manual push button switch 51 is pressed in whereby contacts 52 therein are bridged. This permits current to flow from line 53 through switch 43, switch 42, contacts 54, 55 and 52 in switch 51, contacts 56 of switch 35 and down relay coil 57 to line 58. Switch 59 is merely a heater switch which will open if excess current is flowing in line 58. The flow of current through relay coil 57 immediately shifts the down relay switch 60 toward the left to bridge the four sets of contacts therein, one set of which, namely contacts 61, are holding contacts. This effects rotation of motor 14 in a counterclockwise direction as viewed in Fig. 1. The bridging of holding contacts 61 permits continued flow of current through relay coil 57 even though button 32 is only momentarily depressed. As soon as the spray head starts to move downward the valve 29 is opened by cam bar 31 to furnish spray material into the continuously rotating spray cup 22 to spray the tank T.

After the spray cup passes below the bottom edge of the tank the tripper arm 34 on jib 11 will trip switch 35 to break contacts 56 and to bridge contacts 62 therein. The effect of breaking contacts 56 is to open the down relay coil circuit whereupon the down relay switch will immediately shift toward the right to open the motor circuit and the holding circuit. On the other hand, the bridging of contacts 62 of switch 35 closes a circuit through the up relay coil 63; that is current will then flow from line 53 through switch 43, switch 42, contacts 54 and 64 in switch 51, contacts 62 in switch 35, contacts 65 in switch 36, and up relay coil 63 to line 58. In so energizing the up relay coil 63, the up relay switch 66 is immediately caused to shift to the left to bridge the four sets of contacts therein, of which set, contacts 67 are the holding contacts and thus cause motor 14 to rotate in a clockwise direction as viewed in Fig. 1. Inasmuch as the holding contacts 61 of the down relay switch 60 and the holding contacts 67 of the up relay switch 66 are broken and bridged respectively, it is immaterial that switch 35 only momentarily bridges contacts 62 and momentarily breaks contacts 56. The actuation of relay switch 66 will cause the spray head to move upwardly and again spray the tank T. It is to be noted that motor 14 is provided with a solenoid brake 68 to minimize coasting thereof during reversal or stopping thereof.

When the spray head reaches its upper limit tripper arm 34 will trip switch 36 to momentarily

5 break contacts 65 thereof and to momentarily make contacts 69 thereof. The effect of breaking contacts 65 is to open the up relay circuit, whereupon the up relay switch 66 will drop out thereby breaking the motor circuit and breaking the holding contacts 67 thereof. The momentary bridging of contacts 69 of switch 36 permits current to flow from line 70 through contacts 69 of switch 36 and conveyor relay coil 71 to line 72, 10 whereupon the relay switch 73 shifts to the left to close the circuit to the conveyor motor 45 and to bridge the holding contacts 74, the latter being effective to permit continued energization of relay coil 71 through line 70, contacts 75 of switch 40, contacts 76 of switch 46, and relay coil 71 to line 72. Thus, the conveyor will move until tripper arm 49 thereon trips switch 40 to momentarily break contacts 75 and to momentarily bridge contacts 77 thereof. The momentary 15 breaking of contacts 75 deenergizes coil 71 to permit shifting of relay switch 73 to the right to open the conveyor motor circuit and to break the holding contacts 74. In this way the remaking of contacts 75 will not be effective to restart the conveyor motor 45.

20 The momentary bridging of contacts 77 of switch 40 through lines 78 and 79 makes contacts 52 of manual switch 51 and thus has the same effect as the original manual depressing 25 of the down button 32. This automatically starts downward movement of the spray head to repeat the cycle just described and such automatic operation will continue until the line switches 41 and 50 are opened or until the manually operated stop button 80 in switch 51 is depressed to break contacts 54. The manual conveyor switch 46 is also provided with a stop button 81 to permit stopping of the conveyor at will.

30 In addition to the down and stop buttons in 35 switch 51, there is also a manual up button 82 therein for moving the spray head upwardly at will, the effect of depressing the same being to bridge contacts 83 to energize the up relay coil 63. Switch 46 has a manual start button 84 to 40 run the conveyor motor even though switch 36 or switch 40 or both are inoperative. The safety switches 42 and 43 when tripped are effective to 45 open the relay coil circuit and thus shut off motor 14 in the event that either switch 35 or 36 is 50 inoperative.

55 It is to be understood that while one tank T is being sprayed, another can be loaded on the conveyor. Thus, all that one operator need do is to load tanks on the conveyor. In one preferred arrangement, two machines are placed adjacent one another to simultaneously spray the interior surfaces of two tanks and then the two tanks are moved by the conveyor into another dual machine for spraying the external surfaces 60 thereof and then the tanks so sprayed internally and externally are carried through a drying and baking oven. It can thus be seen that the handling of the tanks is minimized and that the entire process is speeded up and rendered completely automatic for uniformity in results. As indicated above, motor 14 is of the variable speed type whereby the rate of reciprocation can be varied to deposit any thickness of coating desired on to the article being sprayed.

70 While I have described my invention in conjunction with the spraying of the entire interior of hot water tanks, it is to be understood that it is not to be limited to such use but may be used for spraying other than hollow cylindrical articles 75 or for spraying but a portion of the length of

cylindrical articles or articles of shape other than cylindrical.

Other modes of applying the principle of the invention may be employed, change being made as regards the details described, provided the features stated in any of the following claims or the equivalent of such be employed.

I therefore particularly point out and distinctly claim as my invention:

1. In a spraying apparatus, the combination of a supporting frame, a spray head mounted for vertical reciprocation on said frame, a hoisting device controlling both downward gravity movement of said head and upward hoisting movement of said head at equal rates of speed, said hoisting device comprising a reversible power rotated reel and a cable connected to said head and to said reel, actuatable control means for said reel on said frame operative when actuated to reverse the direction of rotation of said reel, and control actuating means carried by said spray head.

2. In a spraying apparatus of the type comprising a spray head reciprocable within a hollow article to be sprayed, the combination of a movable article carrying conveyor and a reciprocable spray head, an electric motor connected to said conveyor for moving the same, a reversible electric motor connected to said head for reciprocating the same, and means for controlling said motors comprising a first switch for interrupting the former at predetermined intervals and simultaneously actuating the latter, and a second switch for interrupting the latter and simultaneously actuating the former.

3. In a spraying apparatus of the type comprising a spray head reciprocable within a hollow article to be sprayed, the combination of a movable article carrying conveyor and a reciprocable spray head, an electric motor connected to said conveyor for moving the same, a reversible electric motor connected to said head for reciprocating the same, and means for controlling said motors comprising a first switch for interrupting the former at predetermined intervals and simultaneously actuating the latter, a second switch for interrupting the latter and simultaneously actuating the former, and a third switch for reversing the latter.

4. In a spraying apparatus, the combination of a supporting frame, and a spray head reciprocably carried by said frame, said spray head comprising a vertically disposed hollow sleeve having its one end connected to a horizontal cross arm slide guided in said frame and its other end opening downwardly, a rotary air motor in such lower end operated by air under pressure supplied through a conduit within said sleeve, a spray cup rotated by said motor, a non-rotatable discharge nozzle within said cup supplying material to be sprayed thereto through a conduit disposed along said sleeve, and a cam operated valve in said latter conduit disposed at one end of said cross arm and engageable by a cam bar disposed vertically along said frame to open said valve during reciprocation of said head.

5. In a spraying apparatus of the type comprising a spray head reciprocable within a hollow article to be sprayed, the combination of a movable conveyor supporting such article thereon, a reciprocable spray head, electrically operated

means for moving said conveyor, electrically operated means for reciprocating said head, and means for controlling said conveyor moving means and said head reciprocating means comprising a first switch simultaneously interrupting operation of said conveyor moving means at predetermined intervals and initiating operation of said head reciprocating means, and a second switch simultaneously interrupting operation of said head reciprocating means and initiating operation of said conveyor moving means.

6. In a spraying apparatus, the combination of a movable conveyor for carrying a hollow article to be internally sprayed to a place of spraying means for moving said conveyor, a spray head at such place of spraying reciprocable toward and away from said conveyor and within such article, means for reciprocating said head, and interconnected control means for said conveyor moving means and said spray head reciprocating means actuated by movement of said conveyor to such place of spraying to interrupt operation of said conveyor moving means and to simultaneously initiate operation of said spray head reciprocating means to thus reciprocate said head toward and away from said conveyor and further actuated by reciprocation of said spray head away from said conveyor to interrupt operation of said spray head reciprocating means and to simultaneously initiate operation of said conveyor moving means for thus carrying the next article on said conveyor to such place of spraying.

7. In a spraying apparatus, the combination of a conveyor for carrying a hollow article to be internally sprayed to a place of spraying, an electric motor connected to said conveyor for moving the same, a spray head at such place of spraying reciprocable toward and away from said conveyor and within such article, a reversible electric motor connected to said head operable in opposite directions for reciprocating said head, and means controlling said motors comprising interconnected switches associated with said conveyor and said head operable to simultaneously interrupt operation of said first motor and initiate operation of said second motor and simultaneously interrupt operation of said second motor and initiate operation of said first motor, and one of said switches being operable to reverse said second motor prior to the interruption of the operation of said second motor and the initiation of the operation of said first motor.
